[57] CLAIM

The ornamental design for a laboratory organizer, as shown and described.

DESCRIPTION

FIG. 1 is a front perspective view of a laboratory organizer, showing my new design;

FIG. 2 is a side elevational view thereof, the opposite side elevational view being identical thereto;

FIG. 3 is a top plan view thereof;

FIG. 4 is a bottom plan view thereof;

FIG. 5 is a left end elevational view thereof; and,

FIG. 6 is a right end elevational view thereof.

The broken line showing in FIGS. 1-6 is for illustrative purposes only and forms no part of the claimed design.
